Primary Examiner — Austin Murphy(74) *Attorney, Agent, or Firm* — Michael Best & Friedrich LLP(57) **CLAIM**

We claim the ornamental design for the wireless hub, as shown and described.

DESCRIPTION

FIG. 1 is a perspective view of a first embodiment of the wireless hub;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

In the drawings, the broken lines disclose environmental subject matter only and form no part of the claimed design.
